F. FABER

SAFETY CLAMP

Filed Aug. 13, 1924

Patented Feb. 3, 1925.

1,524,699

UNITED STATES PATENT OFFICE.

FRANZ FABER, OF JERSEY CITY, NEW JERSEY.

SAFETY CLAMP.

Application filed August 13, 1924. Serial No. 731,728.

To all whom it may concern:

Be it known that I, FRANZ FABER, a citizen of the United States, and a resident of Jersey City, in the county of Hudson and State of New Jersey, have made and invented certain new and useful Improvements in Safety Clamps, of which the following is a specification.

My invention relates to a safety clamp 10 of that type or character which is adapted to open and release a cable or shackle which may be connected thereto when the tension upon the safety clamp becomes excessive.

My safety clamp is primarily intended 15 for the protection of aerial towers and also for the protection of the antenna wires or cables themselves; it being intended that each wire or cable be connected to the tower by means of a safety clamp so that should 20 the tension on the wire become excessive due to abnormal wind velocities or excessive accumulation of snow or ice on the wire, the safety clamp will then open and release the wire and thus protect the wire against break- 25 age or the aerial tower from being over- turned.

My device may also be used wherever a 30 chain, cable, or other member may become subjected to excessive loads and its release- 35 ment under such excessive loads will constitute a protection.

The object of my invention is to provide a device of the above-mentioned character 35 which is simple in construction, involves but few parts, and of such design and nature as to absolutely insure its opening and the 40 release of the cable which is attached thereto, even under the most adverse circumstances, such as might be caused by the accumulation of a coating of ice and snow over the entire device.

A further object is to provide a safety 45 clamp which is not only simple in construction but rugged and durable and capable of withstand- 50 ing high but normal strains without breakage, and, further, withstand the action of the elements over a considerable period of time.

A further object is to provide a safety 55 clamp with a releasing mechanism which may be set to release at a predetermined load and can be absolutely relied upon to release when said predetermined load is reached and at the same time so designed and arranged that there is no danger or likelihood of the device prematurely open-

ing or releasing, the mechanism being in the nature of a lock, so that under ordinary and safe loads the jaws of the clamp are positively held together and under excessive 60 loads the mechanism will be automatically unlocked and the jaws released and caused to fly or spring open and thereby release whatever may be attached thereto.

With the foregoing and other objects in 65 view, which will appear as the description proceeds, my invention consists in the improved safety clamp illustrated in the accompanying drawing and hereinafter described and claimed, and in such variations 70 and modifications thereof as will be obvious to those skilled in the art to which my invention relates, it being understood that changes may be made within the scope of 75 what is claimed without departing from the spirit thereof.

The preferred embodiment of my invention is disclosed in the accompanying drawing, wherein:

Figure 1 is a view in side elevation of my 80 improved safety clamp when subjected to normal loads or tensions;

Figure 2 is a similar view after the safety 85 clamp has been subjected to excessive loads and the jaws have opened;

Figure 3 is a top plan view of the foregoing; and

Figure 4 is a view in section taken on the line 4—4 of Figure 3.

Referring specifically to the several views, 90 wherein similar reference numerals designate corresponding parts throughout, an extensible spring 10 of the elliptical type is provided and includes the sides 11 and 12, the spring being of such character that 95 when tension is applied to the ends thereof and longitudinally of the spring the sides 11 and 12 will move transversely and approach each other. Located at one end of the spring and within the loop formed by 100 the approaching of the sides 11 and 12 to form the end, is a bolt or pivot member 13 and pivotally carried by which are the jaws 14 and 15.

The front extremities of the jaws are op- 105 positely curved, so that when the jaws are closed together as illustrated in Figure 1, a closed eye 16 will be formed and which is adapted to receive the end of a cable, hook or shackle 17 and accordingly secure it to the safety clamp. The jaw 15 is bifurcated 110 to form the two rearwardly extending arms

18, 19. The arm 18 having an inwardly turned end 20 is anchored in place with relation to the spring 10 by the provision of a bracket 21 which is rigidly secured to the 5 side 11 of the spring by the bolts 22. The bracket includes a downwardly extending arm 23 which is provided with the slot 24 extending across the face thereof and which receives the inwardly turned end 20 of the 10 arm 18 therein. Thus the lower jaw 15 is locked against movement with relation to the spring 10. The upper arm 14 is likewise bifurcated and so arranged that, as illustrated in Figure 3, the spring 10 will 15 engage the approximate center of the bolt or pivot member 13 and the jaws will engage the respective ends of the said bolt or pivot. The upper jaw 14 is provided with the rearwardly extending arm 25, which is 20 slightly longer than the corresponding arm 19 of the lower jaw 15, the two jaws being bent in a lateral manner as illustrated in Figure 3, so that the end of the arm 25 will be located directly below but in the same 25 plane as the end portion of the arm 19. A latch 26 is pivoted to the arm 25 and has the forwardly projecting latch 27 which is adapted to extend over and engage the upper surface 28 of the end of the arm 19 and 30 when so positioned hold the jaws 14 and 15 together, as illustrated in Figure 1. The pivot 29, by means of which the latch is secured to the arm 25, is spaced from the main pivot bolt 13 a greater distance than the 35 spacing of the surface 28 from the pivot 13, so that the latch will be inclined in a forward direction and a tension upon the eye or cable 17 tending to open the jaws 14—15 will force the latch rearwardly and cause it 40 to release the arms 19 and 25. A trigger member 30 is slidably received by the bracket 21 and threadedly engages a second bracket 31, which latter is secured to the side 12 of the spring and is locked in adjusted position by the clamping nut 32. The 45 trigger member is provided with a trigger proper 33 and the latch 26 is provided with a rearwardly extending lug or abutment 34, which is adapted to contact with the trigger proper 33 and thereby lock the latch 26 in operable position, as illustrated in Figure 1, holding the jaws 14 and 15 together. The upper extremity of the trigger member 30 is provided with the wrench-engageable surface 35, so that the trigger proper 33 may be moved transversely of the spring and locked in adjusted position. With the parts as 50 thus arranged, the outermost end A of the spring is secured to a wireless tower or other fixture and the cable, chain or other device 17 is fastened between the jaws 14 and 15, as illustrated in Figure 1, the latch having been previously pressed over the end of the arm 19 and locked in such position by the 55 adjusting of the trigger proper 33. The 60 lug 34 has its rear surface rounded or concave, as at 36, as illustrated in Figure 3, so as to provide sufficient surface contact with the trigger member 33, which latter is cylindrical in form. With the parts as thus arranged and the trigger member locked in its position as illustrated in Figure 1, normal strains, while tending to cause the sides 11 and 12 to approach each other, will not be sufficient to cause the trigger member 33 to 65 pass beyond the lug 34. When, however, excessive strains are brought to bear upon the cable, the movement of the sides 11 and 12 will be sufficient to cause the trigger member to be raised and will pass above the 70 upper extremity of the abutment or lug 34, which will immediately allow the latch 26 to spring or fly back, which it does under the action of the pressure of the surface 28 against the overhanging ledge 27 of the latch. The latch, flying back and being forced off of the end of the arm 19, immediately allows the clamping jaws 14 and 15 to open and thereby release the element 75 which was secured or positioned therein. 80

Having thus described and explained my invention, I claim and desire to secure by Letters Patent:

1. A safety clamp comprising a loop shaped spring, a holding device at one end thereof for the securement of a cable, chain, or other element, the opposite end of said spring adapted for securement to a support, a releasing mechanism carried by said spring 95 cooperating with said holding device and locking the same, said releasing mechanism operated upon the transverse movement of the sides of the spring, thereby unlocking said holding device and releasing the element which may be attached thereto. 100
2. A safety clamp comprising an elongated spring with the sides thereof adapted to approach each other under tension, clamping jaws carried at one end of said spring, the opposite end of said spring adapted for securement to a support, a latch secured to one of the jaws and adapted to engage the other of said jaws, and a trigger mechanism carried by one side of said spring, normally engaging and holding said latch in 110 engagement with the said jaws and locking said jaws together, said trigger adapted to be moved by the transverse movement of the side of said spring when the latter is subjected to abnormal stresses and to release said latch for the releasement of said jaws. 115
3. A safety clamp comprising a spring having spaced sides adapted for transverse movement when stresses are applied to the ends of said spring, one end of said spring adapted for securement to a support, the opposite end of said spring carrying hinged jaws, a latch extending between the rear extremities of the jaws and locking the front extremities together, and a trigger 120

125

mechanism carried by the sides of said spring bearing against and holding said latch in engagement with the rear extremities of said jaws, said trigger mechanism 5 adapted to move under abnormal stresses to release said latch and allow for the forced separation of the said jaws.

4. A safety clamp comprising an elongated loop spring, one end thereof adapted 10 for securing to a support, a pair of hinged jaws carried at the remote end of said spring, said jaws provided with rearwardly extending portions, the rear extremity of one jaw secured to the side of the spring, 15 a latch secured to the rear extremity of one jaw and detachably engaging the other jaw extremity, a trigger member secured to the side of said spring opposite to the securing 20 of the jaw to said spring and normally interposed in the path of movement of the latch and preventing the releasement thereof, the sides of said spring adapted to transversely move under abnormal stresses to move the trigger member out of 25 contact with the latch and allow the same to release the said jaws.

5. A safety clamp comprising an elong-

ated loop shape spring with transversely yieldable sides, one end of said spring adapted for securing to a support, a pair of 30 hinged jaws carried at the remote end of said spring, one of said jaws connected to said spring, a trigger member carried by one side of said spring, a latch carried by one of said jaws and detachably engaging 35 the other of said jaws and when so engaged locking the jaws together, a trigger member interposed in the path of movement of the latch and normally preventing the disengagement thereof from said jaws, said 40 trigger member under abnormal stress upon the spring adapted to move out of the path of said latch and allow the same to be forcibly released from said jaws for the release- 45 ment of whatever element may be connected thereto.

Signed at Jersey City, in the county of Hudson and State of New Jersey, this 2nd day of July, A. D. 1924.

FRANZ FABER.
